[57] CLAIM

The ornamental design for a tire mounting press, as shown and described.

DESCRIPTION

FIG. 1 is a top plan view of a tire mounting press showing my new design;

FIG. 2 is a right side elevational view;

FIG. 3 is a front elevational view;

FIG. 4 is a bottom plan view;

FIG. 5 is a rear elevational view;

FIG. 6 is a perspective view; and,

FIG. 7 is a right side elevational view thereof, with the broken line showing of a tire and wheel are environmental and form no part of the claimed design.

FIG. 7 has been drawn on a reduced scale with respect to FIGS. 1-6.

FIG. 1
